PRESSING MACHINE AND CONTROL MECHANISM THEREFOR

Joseph B. Sando, Norwood, and Harold F. Grubler, Cincinnati, Ohio, assignors to The American Laundry Machinery Company, Norwood, Ohio, a corporation of Ohio.

Application March 5, 1934, Serial No. 713,968

28 Claims. (Cl. 68—9)

This invention relates to a press of the type generally used in garment or laundry work and to a control mechanism therefor.

One object of the invention is to provide a press having a bed movable into registration beneath a fixed head and then into final pressure engagement and in which both movements are caused by a piston and cylinder mounted to swivel upon a pivot in vertical alignment beneath the head.

10 In such a press, movement of the piston in one direction swings the bed into registration beneath the head and movement of the piston in the opposite direction causes pressure engagement between the bed and head.

15 Another object of the invention is to provide
in a press of the above mentioned type a relative-
ly long piston stroke impelled by low pressure
fluid for causing the registering movement and
a relatively short piston stroke impelled by high
pressure fluid for causing the final pressure en-
gagement.

Another object of the invention is to provide a rotary valve for automatically connecting opposite ends of a cylinder such as above described with a fluid pressure supply, depending upon the position of the pressing bed.

Another object of the invention is to provide a two hand control for a press of the class described whereby one manual control admits fluid pressure to the operating cylinder to cause registering movement of the press members and automatically latches such members in registering position, while the other manual control admits fluid pressure to the operating cylinder to cause final pressure engagement after the parts reach registering position.

Another object of the invention is to provide, in a press of the class described, means operated automatically by movement of the pressing members into pressure engagement for establishing a fluid pressure circuit for maintaining said press closed.

4.5 In the drawing Fig. 1 is a side elevation somewhat diagrammatic in form showing a laundry press embodying our invention and having our novel control mechanism applied thereto; Fig. 2 is an enlarged detail view of the valve mechanism with the cylinder in the position of Fig. 1; while Fig. 3 is a diagrammatic view of the piston, the rotary valve, and the fluid pressure control valves, with the parts in the position corresponding to the broken line position of the bed shown in Fig. 1.

55 Our press comprises in general a frame 10 sup-

porting a pressing head 11. A bed 12 is supported for vertical movement in a carriage 13 which is movable into and out of registration with the pressing head by means of rollers 14 travelling on rails 15. A cylinder 16 is pivotally mounted on trunnions 17 in vertical alignment beneath the head 11 and a piston 18, reciprocable in the cylinder, is connected by piston rod 19 with stem 20 of the pressing bed. Movement of the piston 18 from the position shown in Fig. 1 downwardly in the cylinder causes the bed 12 to move laterally toward registering position (shown in broken lines) where it is held by a latch 21 and at the same time aligns the piston rod between the pivotal support 17 and the pressing head. With the parts in this aligned position pressure is admitted beneath piston 18 to move it upwardly and cause final pressure engagement between the pressing members.

Our control mechanism comprises in general a rotary valve, the ports of which are actuated by the swivelling movement of cylinder 16 from its forward or open position into its bed-registering position. The valve illustrated has a stationary core 28 and a coaxing sleeve 29 rotatable by movement of cylinder 16 about its pivot. Two manual controls are provided for the fluid pressure supply to the operating cylinder. Manual 26 which controls the pressure supply to the space above piston 18 has a connection with the latch member 21 and a second control handle 39 supplies fluid pressure beneath piston 18 when the parts are in registering position. Fluid under pressure is supplied from a suitable source 22. A reducing valve 23 supplies low pressure fluid to conduit 24 which is controlled by valve 25, which in turn is actuated by handle 26. With the parts in the position of Figs. 1 and 2, this low pressure fluid will travel by way of conduit 27, port 30 in the valve core, and port 31 in the casing, to conduit 32 and the upper end of cylinder 16. At the same time the lower end of cylinder 16 is connected with exhaust by conduit 33, port 34 in the casing, port 35 in the core, conduit 36 and exhaust muffler 37. Ports 30 and 35 are flared as shown to coat with ports 31 and 34 during most of the registering movement. The momentum of the bed and associated parts will complete the small increment of movement necessary to cause complete registration. This moves the bed into registering position shown in broken lines, Fig. 1, which moves the valve and cylinder into the position of Fig. 3.

In this position the upper end of the cylinder 55

is exhausted by way of conduit 32, port 31 in the rotary valve casing, port 35 in the core, and exhaust conduit 36. At the same time, high pressure fluid is conducted through conduit 22, control valve 38 (by depression of control handle 39) through conduit 40, port 41 in the valve core and port 34 in the casing to conduit 33 which communicates with the lower end of cylinder 16. This raises the bed 12 into pressure engagement with the head 11. Piston 18 is then in the dot-dash position shown in Fig. 3.

A maintaining circuit is provided for holding the press in closed position so that the operator may release the control handles. This circuit comprises a conduit 61 communicating with high-pressure conduit 22, a normally open valve 62 which may be located in the same casing with valves 45 and 50, a conduit 63, a normally closed valve 64 which is opened automatically when the press closes, and conduit 65, which communicates through conduit 40, port 41 in the rotary valve core 28, port 34 in the valve casing and conduit 33 with the space beneath piston 18.

The means for automatically opening valve 64 when the press is closed comprises an arm 66 pivoted to the frame and having a free end contacting the stem of valve 64. A bracket 67 depending from the buck pedestal 20 carries a follower 68 in position to engage arm 66 when the bed reaches registering position beneath the head, as indicated in broken lines in Fig. 1. Movement of the bed into pressure engagement with the head causes follower 68 to cam arm 66 in a manner to open valve 64. The maintaining circuit is thus established and the operator releases the control handles, which permits latch 21 to rise to inoperative position. The press is thus held securely closed by line pressure.

Upon completion of the pressing operation valve 62 is closed and valves 45 and 50 are opened. By closing valve 62 the pressure supply for the maintaining circuit is cut off. By opening valve 45 the pressure is relieved from the lower end of cylinder 16 by means of port 42 in the casing which is in communication with port 41 by passage 43 and thence by way of conduit 44, release valve 45 and conduit 46 to the exhaust muffler. Valves 45, 50 and 62 are actuated by arm 47 and link 48 connected with foot treadle 49. Upon the release of pressure beneath piston 18 the bed and associated parts move downward impelled by gravity.

A spring 60 is provided for returning the bed to its forward position. This spring is positioned between the frame and cylinder as shown in Fig. 1. When the bed moves into registration spring 60 is placed in tension. When the pressure is released at the close of a pressing operation and the press opens, the spring returns the bed forwardly. During this portion of the cycle piston 18 moves upward in the cylinder. To facilitate this movement the upper end of the cylinder is connected with exhaust by conduit 32, port 31 in the casing, port 30 in the core, conduit 27, and a branch conduit 27' leading to a valve 50, which is opened simultaneously with the release of final pressure. As illustrated, valve 50 is carried by the same stem as valve 45 and is actuated by foot treadle 49. It will be noted that the lower end of cylinder 16 is vented during the movement of piston 18 upward to prevent the creation of a vacuum. This venting is by way of conduit 33, port 34, port 35 and conduit 36. As explained in connection with the registering movement, ports 30 and 35 will coat with ports

31 and 34 through substantially the entire movement out of registration, and the weight of the parts will be sufficient to complete such movement.

Means is provided to insure approach and separating movement of the pressing members in a direction perpendicular to the pressing surfaces to prevent disarrangement of the lay of the work. The means illustrated comprises a roller or pin 69 carried by the buck pedestal and adapted to engage in a cam slot 70 formed in a member supported on the frame. The cam slot has a portion 71 at its inner end which extends substantially normal to the pressing surfaces, in this case vertically. The bed is thus constrained to move horizontally into and out of registering position but is confined to a vertical movement while approaching and receding from the head.

The operating mechanism for latch 21 includes a bell crank having an upwardly extending arm 51 normally biased rearwardly by spring 52 and movable forwardly by link 53 which has an operative connection with the manual control 26. The bell crank has an arm 54 which lies beneath latch 21, both the latch and the bell crank being pivotally mounted on the frame at 55. A spring 56 normally maintains latch 21 in contact with bell crank arm 54 while permitting yielding movement upward of the latch. When the bed 12 and its carriage are swung into registering position, the latch 21 is cammed upwardly by the detent 57 on the bed carriage and immediately snaps into engagement with the detent impelled by the spring 56. The yielding movement upward of latch 21 is provided to avoid jarring the operator's hold upon control handle 26.

The operation of the press is as follows: With the parts in the full line position of Fig. 1, the operator arranges the lay of the work upon bed 12 and depresses the manual controls 26 and 39. Depression of the control handle 26 moves latch 21 into operative position and admits low pressure fluid to the upper side of piston 18. This swings the bed and its carriage into registering position where they are retained by latch 21. Depression of control handle 39 now causes high pressure fluid to be admitted beneath piston 18 due to the connections established by the rotary valve as the cylinder moved into the position of Fig. 3, that is, with the bed in the broken line position of Fig. 1. The bed then moves into pressure engagement with the head. During this movement follower 68 acts on arm 66 to open valve 64 which establishes the maintaining circuit and the operator releases the manual controls. Upon completion of the pressing operation the operator depresses foot treadle 49, thus closing valve 62 and opening release valves 45 and 50, which exhausts the fluid pressure below piston 18, whereupon the bed and its associated parts move downwardly impelled by gravity and, when pin 69 clears slot portion 71, spring 60 returns the bed to its forward or out of registration position.

The operator must depress both of the control handles, 26 and 39 until the press closes and is thus protected against hand injuries.

What we claim is:

1. In a press of the class described, a fixed pressing head, a pressing bed movable into and out of registration beneath the head, a cylinder pivotally supported beneath the head, a piston in the cylinder having a piston rod connected with said bed, means for moving said piston in one direction in said cylinder to cause registration of the bed with the head and to rotate the

- cylinder about its pivot, said bed in registering position being aligned between the head and the pivotal support for said cylinder, and means for automatically reversing the direction of said piston movement when said bed reaches registering position, whereby said bed is moved into pressure engagement with said head.
2. In a press of the class described, a fixed pressing head, a carriage movable into and out of registration beneath the head, guides for said carriage movement, a pressing bed supported by the carriage for substantially vertical movement relative thereto, a cylinder pivotally supported in vertical alignment beneath the head, a piston in said cylinder having a piston rod connected with said bed and so arranged that movement of said piston rod toward said pivot moves said carriage into registration and movement of said rod away from said pivot when the carriage registers with the head causes pressing approach of said head and bed, a valve having conduit connections with said cylinder on opposite sides of said piston and with a source of fluid pressure supply, means for moving said valve by movement of said carriage into and out of registration, and said valve and its connections being arranged to apply effective pressure alternatively against opposite faces of said piston dependent upon the position of said carriage.
3. In a press of the class described, a fixed pressing head, a carriage movable into and out of registration beneath the head, guides for said carriage movement, a pressing bed supported by the carriage for substantially vertical movement relative thereto, a cylinder pivotally supported in vertical alignment beneath the head, a piston in said cylinder having a piston rod connected with said bed and so arranged that movement of said piston downward moves said carriage into registration and rotates said cylinder about its pivot, and movement of said piston upward when the carriage registers with the head causes pressing approach of said head and bed, a valve rotatable with said cylinder about the axis of said pivotal support, said valve having conduit connections with said cylinder on opposite sides of said piston and with a source of fluid pressure supply, and said valve and its connections being arranged to apply effective pressure alternatively against opposite faces of said piston dependent upon the position of said cylinder.
4. In a press of the class described, a fixed pressing head, a carriage movable into and out of registration beneath the head, guides for said carriage movement, a pressing bed supported by the carriage for substantially vertical movement relative thereto, a cylinder pivotally supported in vertical alignment beneath the head, a piston in said cylinder having a piston rod connected with said bed and so arranged that movement of said piston downward moves said carriage into registration and rotates said cylinder about its pivot, and movement of said piston upward when the carriage registers with the head causes pressing approach of said head and bed, a valve having conduit connections with opposite sides of said piston and with a source of fluid pressure supply and with an exhaust, said valve being arranged in one position to apply effective pressure on the upper face of said piston when the carriage is out of registration, said valve being arranged in another position to apply effective pressure on the lower face of said piston when the carriage is in registration, and means to move said valve from one position to the other as the carriage moves into and out of registration.
5. In a press of the class described, a fixed pressing head, a carriage movable into and out of registration beneath the head, guides for said carriage movement, a pressing bed supported by the carriage for substantially vertical movement relative thereto, a cylinder pivotally supported in vertical alignment beneath the head, a piston in said cylinder having a piston rod connected with said bed and so arranged that movement of said piston downward moves said carriage into registration and rotates said cylinder about its pivot, and movement of said piston upward when the carriage registers with the head causes pressing approach of said head and bed, a valve movable conformably to the movement of said carriage, said valve having conduit connections establishing communication between the upper face of said piston and a source of fluid pressure when the carriage is out of registration, manual means for initiating the flow of fluid pressure to said valve in such position, and said valve having its parts and movements arranged automatically to break said connections and to establish communication between the lower face of said piston and a source of fluid pressure when the carriage is in registration.
6. The combination of claim 5 including, means for retaining the carriage in registration, said means having operative and inoperative positions, and a connection with said manual means for holding said retaining means in operative position when said manual means is in its flow initiating position.
7. The combination of claim 5 including, a second manual means for initiating the flow of fluid pressure to said valve in its last-named position.
8. The combination of claim 5 including, means for releasing the pressure against the lower face of said piston, and means for returning the parts to out of registration position.
9. In combination, a pivotally supported cylinder having a double-acting piston therein, a piston rod rigidly connected with the piston, a track angularly disposed relative to the cylinder axis, a body movable along the track, a connection between said body and said piston rod whereby movement of said piston in said cylinder moves the body along the track and rotates the cylinder about its pivot, a rotary valve having core and casing portions, one of said portions being stationary and the other portion being rotatable by movement of the cylinder about its pivot, said rotatable portion having a first port and a conduit connecting the same to one end of the cylinder, said rotatable portion having a second port and a conduit connecting the same to the other end of the cylinder, said stationary portion having ports arranged to connect the first port to a source of fluid pressure and the second port to exhaust during a relatively large rotative movement of the cylinder and rotative portion in one direction, the momentum of said body movement along the track causing further movement of the parts in the same direction into final position, said stationary portion having other ports arranged in said final position to connect the first port to exhaust and the second port to a source of fluid pressure, means for relieving the last-named pressure, and means for returning the parts in the opposite direction.
10. In a pressing machine, a pair of coacting pressing members one of which is movable into

and out of registration and into and out of pressure engagement with the other, power means for causing movement of said movable member into registration and into pressure engagement with the coacting member, means for operating said power means including a control member shiftable to first and second positions by movement of said movable member out of and into registration respectively, said control member in its first position establishing a power supply circuit with said power means for actuating said power means to cause said into-registration movement, and said control member in its second position establishing a power supply circuit for actuating said power means to cause said into-pressure-engagement movement.

11. In a press having a pair of coacting pressing members one of which is arranged for movement into and out of registration and movement into final pressure engagement with the other member, the combination of fluid pressure actuated power means for causing said movements, means for operating said power means including a valve shiftable to first and second positions by movement of said movable member out of and into registration respectively, said valve in its first position having conduit connections with said power means and a source of fluid supply for actuating said power means for causing said into-registration movement, and said valve in its second position having fluid supply connections for actuating said power means for causing said into-pressure-engagement movement.

12. In a pressing machine, a pair of coacting pressing members one of which is stationary and the other movable into and out of registration and into and out of pressure engagement with said stationary member, double-acting movable abutment means having a pivotal support in alignment with said members in their registering position, a link connecting said abutment means with said movable member, a valve shiftable to first and second positions by movement of said movable member out of and into registration respectively, said valve in its first position establishing fluid supply circuits for actuating said abutment means in one direction to move said movable member to cause into-registration movement thereof, and said valve in its second position establishing fluid supply circuits for actuating said abutment means in another direction to move said movable member into pressure engagement with said stationary member.

13. A pressing machine as in claim 12, including a manually operable valve controlling the fluid supply to said shiftable valve, and means operable by movement of said movable member into pressure engagement for establishing a fluid supply to said shiftable valve independent of said manually operable valve.

14. A pressing machine as in claim 12, including two manually operable valves, one controlling the fluid supply to said shiftable valve in its first position, and the other controlling the fluid supply to said shiftable valve in its second position.

15. In a press of the class described, a fixed pressing member, a movable pressing member, a cylinder and piston motor having a pivotal support, means for guiding said movable member into and out of alignment between said fixed member and said pivotal support, the piston of said motor being connected with said movable member, and fluid pressure means for moving

said piston in two directions, whereby movement of said piston in one direction moves said movable member into alignment and movement of said piston in the other direction moves said movable member into engagement with said fixed member. 5

16. In a press of the class described, a pair of coacting pressing members, one of said members having a preliminary movement laterally into pressing position and a final closing movement, a piston motor having a pivotal support in vertical alignment with the other of said pressing members, the piston of said motor having a connection for moving said movable member, and fluid pressure means for moving said piston 10 in two directions, whereby to cause said preliminary movement when said piston moves downward and to cause said closing movement when said piston moves upward.

17. In a press of the class described, a fixed 20 pressing head, a carriage movable laterally into and out of registration beneath the head, a pressing bed supported by the carriage and slideable vertically therein, a piston motor pivotally supported on the frame in vertical alignment beneath the head, fluid pressure means for moving said piston in two directions, a connection between said piston and bed whereby to move said carriage into registering position when said piston moves downward and to raise said bed into pressing engagement with the head when the piston moves upward, and releasable means for retaining said bed in registering position. 30

18. In a press of the class described, a frame, 35 a pressing head supported by the frame, a carriage movable into and out of registration beneath the head, a pressing bed supported by the carriage and slideable vertically therein, a cylinder having a pivotal support on said frame vertically aligned beneath the head and below 40 the path of travel of said carriage, a piston having a piston rod rigidly connected therewith in said cylinder, a direct connection between said rod and said bed, and means for supplying fluid pressure successively to the upper and lower 45 ends of said cylinder.

19. In a press of the class described, a fixed 50 pressing head, a pressing bed movable laterally into and out of registration beneath the head, a cylinder pivotally supported in vertical alignment beneath the head, a piston in the cylinder having a piston rod directly connected with said bed, and fluid means for moving said piston in both directions in said cylinder whereby downward movement of said piston causes registration 55 of the bed with the head and rotates the cylinder about its pivot and upward movement of said piston causes pressing engagement between said bed and head.

20. In a press of the class described, a fixed 60 pressing head, a piston motor pivoted in vertical alignment beneath the head, a pressing bed movable into and out of alignment between said head and pivot, guides limiting the path of said bed movement, a connection between said bed 65 and the piston rod of said motor, operating means for moving said piston downward to cause movement of said bed and piston rod into aligned position, means for holding said bed in aligned position, and said operating means being adapted 70 to move said piston upward to cause pressing approach between the bed and head.

21. In a press of the class described, a fixed 75 pressing head, a carriage movable laterally into and out of registration beneath the head, guides

- for said carriage movement, a pressing bed supported by the carriage and slideable vertically therein, a cylinder pivotally supported in vertical alignment with the center of the head, a 5 piston in said cylinder having a piston rod connected with said bed whereby movement of said piston downward moves said carriage into registration and movement of said piston upward when the carriage registers with the head causes 10 pressing approach of said head and bed, and means for supplying fluid pressure to move said piston in each direction.
22. In a press of the class described, a fixed 15 pressing head, a carriage movable into and out of registration beneath the head, guides for said carriage movement, a pressing bed supported by the carriage for substantially vertical movement relative thereto, a cylinder pivotally supported in vertical alignment beneath the head and below 20 the path of travel of said carriage, a piston in said cylinder having a piston rod connected with said bed whereby movement of said piston downward moves said carriage into registration and rotates said cylinder about its pivot and movement of said piston upward when the carriage 25 registers with the head causes pressing approach of said head and bed, means for supplying fluid pressure to each end of the cylinder, said cylinder being of such length that said piston traverses substantially the entire cylinder in its 30 downward movement, and said bed in its registering position being spaced a short distance from said head, whereby a small volume of fluid causes pressing approach of said head and bed.
23. In a pressing machine, a frame, a pressing head carried thereby, a coacting pressing bed movable into and out of registration beneath said head, guiding means for said bed movement, means for locking said bed in its registering 35 position, and means for moving said bed comprising a double-acting cylinder and piston motor, a link connected with said motor and with said bed in such a manner that movement of said piston in one direction moves said bed into 40 registering position and locks it there, said link being constructed and arranged in a manner to be positioned by said into-registration bed movement in alignment below said registering head and bed, and said connection between said 45 link and cylinder and piston motor being arranged to extend said link to raise said bed against said head by movement of said piston in the other direction.
24. In a pressing machine, a frame, a fixed 50 pressing member carried thereby, a coacting pressing member movable into and out of registration with said fixed member, and means for moving said movable member comprising a double-acting cylinder and piston motor, a link connected with said motor and said movable member in such a manner that movement of 55 said piston in one direction moves said movable member into registering position, said link being constructed and arranged in a manner to be positioned in alignment with said registering pressing members by said into-registration movement of said movable member, and said connection between said link and motor being arranged to extend said link to move said movable pressing member into engagement with said fixed pressing member by movement of said piston in the other direction.
25. In a pressing machine, a pair of coacting relatively movable pressing members having a preliminary relative movement to position them adjacent one another and a final relative movement into pressure engagement, and a double-acting cylinder and piston motor having operative connections with at least one of said pressing members whereby to cause said preliminary relative movement by a stroke of said motor in one direction and to cause said final relative movement by a stroke of said motor in the other direction.
26. In a pressing machine, a pair of coacting relatively movable pressing members having a preliminary relative movement to position them adjacent one another and a final relative movement into pressure engagement, a double-acting cylinder and piston motor having operative connections with at least one of said pressing members whereby to cause said preliminary relative movement by a stroke of said motor in one direction and to cause said final relative movement by a stroke of said motor in the other direction, and means for automatically reversing said motor upon completion of said preliminary relative movement.
27. In a pressing machine, a pair of coacting relatively movable pressing members having a preliminary relative movement to position them adjacent one another and a final relative movement into pressure engagement, a double-acting cylinder and piston motor having operative connections with at least one of said pressing members whereby to cause said preliminary relative movement by a stroke of said motor in one direction and to cause said final relative movement by a stroke of said motor in the other direction, a control valve having two positions, one for effective supply of motive fluid to said motor for causing each of said strokes, and means for moving said valve from one of its positions to the other upon completion of said preliminary relative movement.
28. A pressing machine as in claim 25, and including manually controlled fluid supply means for causing said preliminary-movement-producing stroke of said motor, and fluid supply means actuated automatically upon completion of said preliminary relative movement for causing said final-movement-producing stroke.
